Specification for Design.

Patented Apr. 6, 1915.

Application filed November 24, 1914. Serial No. 873,836. Term of patent 14 years.

To all whom it may concern:

Be it known that I, FRANK L. ORDWAY, a citizen of the United States, and a resident of Salem, in the county of Essex and State of Massachusetts, have invented a new, original, and ornamental Design for a Toy Pop-Gun, of which the following description, in connection with the accompanying drawings, is a specification.

In the drawings: Figure 1 shows a plan view of a toy spring popgun having the design of my invention; Fig. 2 shows a side

elevation thereof; and Fig. 3 shows an underneath plan thereof.

What I claim is:

The ornamental design for a toy pop-gun as shown.

In testimony whereof I have signed my name to this specification, in the presence of two subscribing witnesses.

FRANK L. ORDWAY.
